UNITED STATES PATENT OFFICE

FRANCIS P. SWALLOW, OF WORCESTER, MASSACHUSETTS, ASSIGNOR TO UNITED STATES ENVELOPE COMPANY, OF SPRINGFIELD, MASSACHUSETTS, A CORPORATION OF MAINE

DISPENSING CONTAINER

Application filed July 20, 1931. Serial No. 551,893.

The present invention relates to a dispensing container for nested articles, such as paper cups of the open-mouth type which are adapted to be withdrawn singly from a container when required for use, and particularly to an adapter for dispensing containers by which containers used for dispensing flat packed cups may be arranged for dispensing open-mouthed cups.

10 The replacement of flat drinking cups, which require opening by the user before they can be filled, for the more economical and sanitary drinking cups of the type disclosed in the Dickerson reissue Patent 17,553, has heretofore necessitated the provision of an entirely new dispensing container for the new type of cups, since open-mouthed cups are not adaptable for dispensing from containers of the flat cup dispensing type, for example, the type of container disclosed 20 in Patent No. 1,333,045 granted to Swift on March 9, 1920, this container being intended for dispensing flat stacked cups. The substitution of a container of the open-mouthed cup dispensing type, which is usually of a 25 different shape from the container of the flat cup dispensing type, leaves an unsightly appearance on the surface to which the containers are secured; and in certain cases 30 where the container is mounted in a recess in the wall or surface, the substituted container does not fit in the same recess in which the original container was mounted and accordingly cannot be used.

35 According to the present invention an adapter including a dispensing passage and dispensing slot, of a construction to permit dispensing of open-mouthed nested cups, is formed as a unit and is arranged to be substituted for the dispensing opening of a 40 container for dispensing flat cups of the type shown in the above cited Swift patent. In this manner, containers for dispensing flat cups may be readily adapted to the dispensing of open-mouthed nested articles without 45 changing the position or the outward appearance of said container.

The container with the adapter therein is arranged to present a small portion of 50 the outer cup of the stack in a position for

delivery through the dispensing slot, thereby to permit withdrawal of said outermost cup from the container without permitting the user's hands to come in contact with the inner side of said cup or with any of the other cups in the stack. The adapter preferably is arranged to maintain a cup always in position for delivery by permitting only a limited movement of the stack within the container whereby a portion of the outermost cup is always presented through the dispensing slot. The above and other advantageous features of the invention will more fully appear from the following description, reference being had to the accompanying drawings in which:

Fig. 1 is a front elevational view of a container embodying the invention.

Fig. 2 is a side elevational view of the container shown in Fig. 1.

Fig. 3 is a vertical sectional view along the line 3—3 of Fig. 1 looking in the direction of the arrows.

Fig. 4 is an inverted plan view of the lower end of the container.

Fig. 5 is a horizontal sectional view along the line 5—5 of Fig. 3 looking in the direction of the arrows.

Fig. 6 is a perspective view of the adapter of the invention, removed from the container.

Fig. 7 is a view corresponding to Fig. 3, showing the container before the insertion of the adapter.

Fig. 8 is a perspective view of a paper cup of the open-mouth type, which the container is adapted to dispense.

Like reference characters refer to like parts throughout the drawings.

The container comprises an elongated substantially rectangular body 1 closed on all sides except at its lower end where a dispensing slot 2 of a peculiar shape is provided. As shown in Fig. 3, the body 1 is arranged to enclose a stack of nested cups 3 with the wedge-shaped end portion 4 of the lowermost cup of the stack depending downwardly through the slot 2 so that the portion 4 may be readily grasped by the user.

when it is desired to withdraw a cup from the container.

Referring to Fig. 8, a single cup 3 is shown of the type best adapted for dispensing from the container of the invention, although other similar articles may also be handled. The cup provides an open self-distended mouth, elliptical or substantially circular in form, with a downwardly tapering body terminating in a wedge-shaped end portion 4 providing, adjacent the lower end, substantially flat sides so that the cup may be readily grasped by the portion projecting through the dispensing slot 2, as best shown in Fig. 3. The cups 3 are preferably formed of paper possessing the requisite stiffness for the cups always to remain in the open distended position, and obviously cups of this type are readily nested within each other to form a stack, as shown in Fig. 3, the weight of which stack tends to carry the lower end thereof downwardly into the dispensing slot 2 of the container.

The container construction, except for the bottom end wall, is similar to the construction of the above cited Swift patent. It is sufficient, for the purposes of the present application, to note that the container provides an enclosing shell 5, bent or pressed to form a rear wall 6, side walls 7, and in-turned front flanges 8 as shown in Fig. 3. At their lower ends the side walls 7 have forwarded disposed extensions 10 and said side walls 7 have their lower edges 11 inclined downwardly from the extension 10 toward the rear as shown in Figs. 2 and 3. The rear wall 6 provides screw holes 12 to permit attachment of the cabinet to a supporting surface 13. The in-turned front flanges 8 support a transverse vertical plate 14 which constitutes an extension of said flanges 8 adjacent the extensions 10 provided by the side walls 7. The plate 14 is bent outwardly at 15 near its lower end to lie substantially normal to the lower edges 11 of the side walls 7 and is provided at its lower end with an upwardly turned tongue 16 to provide a central bearing or support for the inner ends of pins 17 which extend inwardly through openings in the extensions 10 of the side walls 7. Similar pins 18 extending inwardly from the lower ends of side walls and are supported at their inner end by a bead or bearing 20 formed from the material at the lower end of the rear wall.

In the construction of Fig. 7 which shows the lower portion of the cabinet with the construction therein for dispensing flat cups, the pins 17 and 18 provide pivotal supports for hinged doors 21, these doors having beads or bearings 22 surrounding the respective pins 17 and 18 on opposite sides of the bearings 16 and 20. The doors are normally held yieldingly against stops 23,

formed by projecting tongues on the plate 14 and the rear walls. The doors are arranged to yield outwardly to permit removal of a cup from within the container and thereafter spring inwardly to close the discharge opening and support the cups in the stack. An opening 24 is provided between the adjacent free edges of the doors to permit the user to grasp the lowermost cup for withdrawal thereof.

The upper edge of the plate 14 is overturned as at 25 to receive and support a concave plate 26, the latter extending transversely of the container to close the outside of the receptacle, forming a continuation of the flanges 8 and following the contour of the upper edges of the extensions 10. The front edges of the extensions are joined by a substantially vertical plate 27 whose lower edge is inturned as at 28 to close the space between the lower ends of plates 14 and 27, said inturned portion terminating adjacent the outward bend 15 of plate 14. At its upper edge adjacent its inter-section with the curved plate 26, the plate 27 provides a pair of beads 29 for the support of a shaft 30 on which is journaled a swinging front closure 31 for the container, said front having integral beads 32 along its lower edge to provide a hinged connection with said shaft 30. The front is curved inwardly and thereafter rises substantially vertically to coincide with the front edges of the side walls 7 when in closed position, the upper end of said front being turned rearwardly and horizontally to provide a closure for the top of the cabinet; the sides of the front and top are flanged as at 33 to overlie the side walls 7. The front closure carries a spring latch 34 engaging with a transverse plate 35 which connects the flanges 8 adjacent the top edges, said latch being arranged to hold said front closure in closed position, an outwardly extending end 36 being provided on said spring latch in order to release said latch when it is desired to open the container as for refilling.

When it is desired to dispense, from the above described cabinet construction, open-mouthed wedge-shaped cups instead of the flat type of cups, the hinged doors 21 are removed by withdrawal of the pins 17 and 18 and the substitution therefor of a dispensing slot and passage shown in perspective in Fig. 6 and in operative relation with the container in Figs. 1 to 5.

Referring particularly to Fig. 6, a substantially rectangular plate 37 is provided along the longitudinal edges adjacent opposite corners with beads or bearings 38 through which the pins 17 and 18 are adapted to extend when the adapter is placed within the container as shown in Fig. 3, the plate 37 being of the size to substantially fill the lower end of the container

between the beads 16 and 20, the beads 38 then being in alinement with the beads 16 and 20. The plate is provided with an elongated slot 40, adjacent one edge thereof, 5 of generally narrow elliptical form with open ends as shown most clearly in Fig. 4. The opposite longitudinal edges of the slot are provided with upstanding walls 41 and 42 which extend obliquely to the plane of 10 the plate in diverging relation, so that when the adapter is within the container, the walls will extend upwardly, the wall 41 extending toward the rear wall of the container and the wall 42 extending toward the 15 front wall. The walls 41 and 42 diverge to form a substantially wedge-shaped dispensing passage corresponding in contour to the shape of the cup, said passage having open ends corresponding to and leading 20 down to the open ends 40' of the dispensing slot 40. The walls 41 and 42 adjacent the upper end of the dispensing passage are bent into substantially horizontal, or slightly upwardly extending, relation to engage 25 with the sides of the container, the contour of the upper and outer edges of the walls 41 and 42 forming substantially a rectangle corresponding in dimensions to the rectangular cross-section of the container. The 30 rear wall 41 is provided at the upper edge of the dispensing passage and centrally of the rear edge of said wall with an upstanding extension 43 in substantially parallel relation to the rear wall of the container. 35 Said extension is provided with a pair of offset portions 44 and 45 forming downwardly extending prongs which are adapted, during the dispensing of cups from the container, to engage with a portion of the 40 open mouth of one of the cups within the container to limit the movement of the lower portion of the stack of cups inwardly of the container. The plate 37 is provided with an upwardly depressed portion 46 directly in back of the slot 40 to provide a 45 greater grasping area for the rear surface of the cup without causing the cup to project a greater distance beyond the slot.

It will be apparent that a dispensing construction such as shown in Fig. 7 may be readily converted into the construction of Fig. 3 by the removal of the pins 17 and 18 and the substitution for said dispensing member of the dispensing slot and passage 50 shown in Fig. 6, the latter being maintained in position within the container by reinsertion of the pins 17 and 18, the rectangular plate member of said adapter forming a lower wall for the container. It is found desirable in certain arrangements to remove the stops which held the swinging doors in position, in order to permit the adapter to be mounted in the position desired.

When the adapter of Fig. 6 is mounted 60 within the container, as shown in Figs. 1 to

5, the container is closed at the bottom by the rectangular plate 37 which extends parallel to the lower edges 11 of and between the side walls, the slot 40 being adjacent the front of the container, Figs. 3 and 4, the rear 70 wall 41 of the dispensing passage extending upwardly from the edge of the slot toward the rear wall, at a substantial angle to the rear wall, the extension 43 extending upwardly in parallel relation to said rear wall 75 with the prongs directed toward the dispensing slot. The front wall 42 of the dispensing passage extends substantially vertically upwardly into engagement with the front wall of the container. The configuration of the walls of the dispensing passage is such that the normal center line of the passage extends at an angle to the center line of the stack of 80 cups within the container, and the projecting portion of the stack is thus presented forwardly and downwardly. The projecting portion is thus readily grasped by the user for removal of a cup, especially when the container is mounted within a recess in the wall. The upper ends of the dispensing passage walls flare outwardly substantially into engagement with the walls of the container 85 whereby cups inserted through the top of the container are directed into the wedge-shaped dispensing passage, and cannot be 90 caught within the container.

Since the cups are directed forwardly at an angle to the center line of the stack, the cups tend to separate from each other adjacent the rear of the container where the direction of the stack is changed, that is, adjacent the upper end of the dispensing passage as shown in Fig. 3. By locating the prongs at this point of separation, it will be 100 seen that the prongs may readily engage the open mouths of successive cups, as the outermost cups are withdrawn from the stack. It will be noted that the cups substantially fill the space between the front wall and the prongs, so that the cups cannot tip forwardly out of engagement with said prong. The prongs are arranged to permit a substantial vertical movement of the stack within the 105 container to permit a single cup to be freely withdrawn at one time, although the prongs 110 act to prevent an excessive movement of said stack.

I claim,

1. An adapter for attachment to a dispensing container, the latter being normally arranged to receive and support a stack of normally flat cups, said adapter providing, when attached to said container, for the dispensing of nested open-mouthed wedge-shaped articles, said adapter comprising a lower end wall member having means at opposite edges to permit attachment of said member to said container, said member having an elongated slot therein and walls extending from the edges of said slot in di- 120 125 130

verging relation to form a substantially wedge-shaped passage.

2. An adapter for attachment to a dispensing container, the latter being normally arranged to receive and support a stack of normally flat cups, said adapter when secured to said container providing for the support in and dispensing from said container of a stack of nested open-mouthed wedge-shaped articles, said adapter comprising a substantially rectangular member having a slot longitudinally therein, walls extending from opposite edges of said slot obliquely to said member and in diverging relation, said walls providing a substantially wedge-shaped passage to said slot between said walls, and means on said adapter to permit securement of said adapter to said container.

20 3. An adapter for attachment to a dispensing container, the latter being normally arranged to receive and support a stack of normally flat cups, said adapter when secured to said container providing for the support in and dispensing from said container of a stack of nested open-mouthed wedge-shaped articles, said adapter comprising a substantially rectangular member having a slot longitudinally therein, walls extending from opposite edges of said slot obliquely to said member and in diverging relation, said walls providing a substantially wedge-shaped passage to said slot between said walls, said walls flaring outwardly at 35 the end remote from the slot whereby the outer edges of said walls define substantially a rectangle.

4. An adapter for attachment to a dispensing container, the latter being normally arranged to receive and support a stack of normally flat cups and having a removable end, said adapter when secured to said con-

tainer providing for the support in and dispensing from said container of a stack of nested open-mouthed wedge-shaped articles, said adapter comprising a lower end wall forming member adapted to form the end of said container and having means along opposite edges by which to secure said member to said container, said member having an elongated slot therein, walls extending upwardly from said slot and in diverging relation to provide a substantially wedge-shaped dispensing passage, the upper edges of said walls corresponding substantially in contour to the cross-section of the container.

5. A dispensing container adapted to receive and support a stack of nested open-mouthed wedge-shaped articles substantially centrally therein, said container comprising front, side and rear walls, a forwardly and upwardly sloping lower end wall having a slot therein through which a portion of said stack is adapted to extend, said slot being located forwardly of the vertical center line of said container and forwardly of the center line of the stack of articles therein, said container having a dispensing passage therein extending upwardly and rearwardly from said slot for directing the articles in the stack toward and through said slot, said passage also extending at an angle to the vertical center line of the container and the center line of the stack of cups therein, and means within the container and adjacent the rear wall thereof for limiting the upward movement of the stack within the container, said dispensing passage, by its angular relation to the center line of the stack, procuring separation between successive articles adjacent said means, whereby said means engages the open mouth of one of said articles.

FRANCIS P. SWALLOW.
